Application October 17, 1950, Serial No. 190,630

1 Claim (Cl. 250—36)

(Granted under Title 35, U. S. Code (1952); sec. 266)

The invention described herein may be manufactured and used by or for the Government for governmental purposes without payment to me of any royalty thereon.

This invention relates to a device for generating radio frequency energy and particularly to an arrangement for generating high power radio frequency energy directly from an array of gaseous discharge devices. The invention is particularly suited to the generation of pulses of high frequency energy, such as required, for example, in the Loran navigational system, but may also be used to generate continuous radio waves.

It is accordingly an object of the invention to provide improved means for generating high power radio frequency energy, in the form of pulses occurring at regular or irregular intervals or in the form of a continuous wave, which possesses a high degree of radio frequency stability and accuracy of time reference with respect to the triggering pulses.

Another object of the invention is to provide apparatus for generating radio frequency pulses of stable and easily reproducible envelope shape.

A further object of the invention is to provide a radio frequency generating device which achieves a high degree of power conversion efficiency at high power levels.

An additional object of the invention is to provide high power radio frequency generating apparatus which requires little input signal driving power for its high power output condition, or, in other words, which has a high power gain.

A more complete description of the invention will be given in connection with the accompanying drawings, in which

Fig. 1 shows a high frequency pulse generating circuit in accordance with invention employing five gaseous discharge tubes;

Fig. 2 shows the time relationship between triggering pulse and generated high frequency pulses; and

Fig. 3 shows an alternative method of operating the circuit of Fig. 1 in which the sequence of gaseous discharge tubes are utilized more than once in the generation of a high frequency pulse.

Referring to Fig. 1, the circuit shown operates to generate a series of pulses of high frequency energy. The circuit employs five gaseous discharge devices, such as thyratron tubes, numbered 1 through 5. The number of gaseous discharge devices needed depends principally upon the desired frequency of the generated wave and the desired pulse width, since the number of cycles of high frequency energy composing each pulse is determined principally by the number of tubes used. The invention, therefore, is not limited to the number of tubes shown, by way of example, in Fig. 1.

The tubes 1 through 5 are connected in series with condensers 6 through 10, respectively, across the primary winding of transformer 11 so that each condenser may discharge through the primary winding when the corresponding tube is in a conductive state. When the tubes are in

a nonconductive state the condensers 6—10 may be charged from direct current source 12 through resistors 13—17, respectively, and the primary winding of transformer 11. The condensers 6—10 discharge more rapidly than they charge since discharge takes place through the comparatively low plate resistance of the gaseous tubes whereas the condensers must be charged through the comparatively high resistance of resistors 13—17.

The control grids of tubes 1—5 are normally biased 10 beyond the cut-off or breakdown point, for the particular anode voltage employed, by bias potential from direct current bias source 18 acting through resistors 19—23. The grid circuits of adjacent tubes in the chain of tubes 1—5 are connected together by means of pulse delay networks 16—24—27. The delay circuits are each adjusted to produce a delay equal to the period of the radio frequency wave to be generated. These circuits may be of any known type capable of producing the required delay such, for example, as delay lines, tuned circuits, multivibrators, or phantastron circuits, the latter being a delay circuit of the type described on pages 58—64, chapter 2, of "Principles of Radar," second edition; M. I. T. Radar School Staff; McGraw-Hill Book Company. Input terminals 28 are provided for applying input signal pulses to the grid of tube 1. The output radio frequency wave is taken from output terminals 29 connected to the secondary of transformer 11. The secondary winding is tuned by condenser 30 to resonate at the desired output frequency.

The above-described circuit operates, upon the application of a trigger pulse to the input terminals 28, to generate a pulse of high frequency energy. Assume, for example, that a train of equally time spaced trigger pulses, such as shown at 31 in Fig. 1, are applied to input terminals 28. Upon application of one of these pulses to the grid of gaseous tube 1 this tube becomes conductive and allows condenser 6, which has previously charged through resistor 13 to the potential of source 12, to discharge through the tube and the primary winding of transformer 11. The resulting pulse of energy induced in the secondary winding 32 shock excites the resonant circuit 32—30 into oscillation at its resonant frequency. As already stated, the delay produced by each of networks 24—27 is made exactly equal to the period of resonant circuit 32—30. Therefore, at the end of one cycle of oscillation of the resonant circuit the trigger pulse will have reached the grid of gas tube 2 which thereupon becomes conductive permitting condenser 7 to discharge through the primary of transformer 11 with the result that a second pulse of energy is applied to the resonant circuit 32—30. Similarly, at the end of the second cycle of oscillation of the resonant circuit the trigger pulse will have reached tube 3 and so on until the remaining condensers 8, 9 and 10 have been discharged through the primary of transformer 11. The resulting high frequency pulses produced at the output terminals 29 are shown in Fig. 2b, the trigger pulses 31 being shown on an expanded time scale at (a).

The number of oscillations of tuned circuit 32—30 that will be produced by each pulse of energy applied thereto depends on the amount of damping present. In cases 60 where more than one cycle of oscillation results from the shock excitation of the circuit it will be evident that the first cycle of each oscillation will be reinforced by the second cycle of the preceding oscillation, the second cycle of oscillation will be reinforced by the third cycle of the preceding oscillation and so on. The high frequency pulse representations of Fig. 2b are based on the use of the circuit shown in Fig. 1 and a degree of damping that results in three cycles of oscillation for each shock excitation of the resonant circuit. Since one gaseous tube is used to generate each damped oscillation the number of cycles in the high frequency pulse is determined primarily by the

number of tubes used in the sequence, and secondarily by the number of cycles contained in each damped oscillation.

It is, of course, not essential that the time spacing between pulses 31 be uniform as shown in Figs. 1 and 2. This spacing may be varied in any desired way, however, in cases where a complete high frequency pulse is to be generated for each trigger pulse the spacing between trigger pulses should not be less than the duration of the high frequency pulse envelope. Also the interval between pulses must not be less than the deionization time of the gaseous tubes used.

In case where the high frequency pulse envelope duration desired is greater than the deionization time of the gaseous tubes used the sequence may be used more than once during each output pulse. This may be accomplished by the use of an accurately time-spaced multiple trigger pulse train such, for example, as shown in Fig. 3a. The resulting high frequency pulses, for a five tube sequence such as shown in Fig. 1, are shown in Fig. 3b. The interval t between pairs of trigger pulses must be exactly equal to the period of the high frequency multiplied by the number of tubes in the sequence. Although Fig. 3 shows the trigger pulses in groups of two and three it is of course possible to employ any desired number of pulses in a group. It will also be evident from the above that a continuous high frequency wave could be generated by a continuous train of trigger pulses separated by intervals t .

The invention may be used for the broadcast of speech, music and similar intelligence by frequency modulation of the triggering pulses or amplitude modulation of the high frequency output energy.

We claim:

Apparatus for generating high frequency energy, said

apparatus comprising a resonant circuit tuned to the desired frequency of said energy, coupling means for applying pulses of energy to said resonant circuit, said coupling means having a pair of input terminals, a plurality of 5 gaseous discharge tubes each having at least an anode, a cathode and a control grid, a plurality of branch circuits connected in parallel across said input terminals, each of said branch circuits comprising a condenser and the anode-cathode path of one of said tubes connected in series, means for charging said condensers to a predetermined 10 potential, a grid circuit connected between the grid and cathode of each of said tubes, means forming part of said grid circuits for biasing the grids of said tubes sufficiently 15 to render said tubes normally nonconductive at the said predetermined potential to which said condensers are charged, means coupling said grid circuits in cascade, said means comprising delay networks, each producing a delay equal to the period of the frequency to which said resonant circuit is tuned, connected between adjacent pairs 20 of the grid circuits in said cascade, means for applying a positive trigger pulse to the first of the grid circuits in said cascade, and means for coupling said resonant circuit to a load circuit.
